UNITED STATES PATENT OFFICE.

JOHN D. DAVIES, OF BUTTE, MONTANA.

MATTE AND SLAG SEPARATING WELL.

SPECIFICATION forming part of Letters Patent No. 542,148, dated July 2, 1895.

Application filed September 18, 1894. Serial No. 523,402. (No model.)

To all whom it may concern:

Be it known that I, JOHN D. DAVIES, of Butte city, county of Silver Bow, and State of Montana, have invented a new and Improved 5 Matte and Slag Separating Well, of which the following is a full, clear, and exact description.

The invention consists of a well provided with two compartments of different heights 10 connected with each other at or near the bottom, one compartment being provided with an outlet for the slag and the other with an outlet for the matte.

The invention also consists of certain parts 15 and details and combinations of the same, as will be fully described hereinafter, and then pointed out in the claim.

Reference is to be had to the accompanying drawings, forming a part of this specification, 20 in which similar letters of reference indicate corresponding parts in all the figures.

Figure 1 is a perspective view of the improvement with parts broken out. Fig. 2 is a sectional side elevation of the improvement. 25 Fig. 3 is a rear end perspective view of part of the improvement; and Fig. 4 is a plan view, partly in section, showing the separating-well in connection with the furnace.

The improved matte and slag separating 30 well is provided with a casing A, made of a suitable material and formed with two compartments B and C, located one alongside the other and both preferably lined with fire-brick or other suitable material. The larger 35 and higher compartment B is adapted to receive the molten metal from the tap-hole of the furnace, and the said compartment is provided at its rear end and on the top edge with a notch D, forming an outlet for the slag passing through the notch upon a suitable spout D' for leading the slag to one side of the well. Next to the notch D is arranged a vertically-disposed slot E, adapted to be closed by a metallic plate or gate F, held in brackets G 40 secured to the end of the casing, as is plainly shown in Fig. 3. In the partition H', between the compartments B and C, is arranged an opening H, located near the bottom of the casing A and serving to conduct the matte

from the compartment B to the compartment 50 C, the latter being provided at its upper end and on the top edge with a matte-discharge notch J, leading to a suitable spout J' for carrying the matte to one side into a suitable receptacle to be further treated. 55

It will be observed that the spout J' is located at a lower level than the spout D'. The partition H' and the lining A' are made of refractory material, such as a composition of one part of fire-clay and five parts of quartz. 60

In the end of the compartment C is arranged a tap-hole I, located opposite the tap-hole H, as is plainly shown in Figs. 1 and 2; and above this tap-hole I in the top of the end of the compartment C is formed a 65 notch K for guiding a bar or other tool to the tap-hole H, to open the same when required, and as hereinafter more fully described.

The operation is as follows: The casing A with the tap-holes H and I close in the usual 70 manner, and the slot E, closed by the plate F, is placed in such a position near the furnace U that when the latter is tapped then the molten metal from the furnace flows into the compartment B, with the matte on the bottom 75 and slag on the top. When a sufficient amount of molten metal has accumulated in the compartment B, then the tap-hole H is opened or tapped to permit the matte to flow through the tap-hole H into the compartment 80 C. The lightest portion of the slag flows out through the spout D', so that an automatic skimming is obtained. After the skimming is over the operator opens the slot E by removing the plate F to permit the slag to run 85 out of the compartment B. When about eight inches of matte and one inch of slag is left in the compartment B, then the tap-hole I is opened and the matte and the slag run out to empty the casing. Now, the door of the 90 furnace will be as near the head of the well as possible, so that there will be a distance of about two and one-half feet from the discharge-spout of the furnace to the slag-spout.

Having thus fully described my invention, 95 I claim as new and desire to secure by Letters Patent—

A matte and slag separating well, provided

with a large compartment and a small compartment connected with each other at or near their bottoms, a slag discharge and a slot in one end of the large compartment, and 5 a metallic plate held in brackets on the end of the said large compartment and adapted to close the slot therein, the smaller compart-

ment being provided with a matte discharge and a tap-hole, substantially as shown and described.

JOHN D. DAVIES.
